UNITED STATES PATENT OFFICE

JOSEPH SIMON, OF CHICAGO, ILLINOIS.

DESIGN FOR A CONFECTION.

SPECIFICATION forming part of Design No. 28,957, dated June 28, 1898.

Application filed January 31, 1898. Serial No. 668,681. Term of patent 3½ years.

To all whom it may concern:

Be it known that I, JOSEPH SIMON, a citizen of the United States, residing at Chicago, in the county of Cook and State of Illinois, have invented a certain new and novel Design or a Confection; and I do hereby declare the following to be a full, clear, and exact description of the invention.

My invention relates to a novel design for confection for ornamenting pastry and confections, the object being to provide an attractive article of this character; and it consists in the features of the design hereinafter described and claimed.

In the accompanying drawings, illustrating my design, Figure 1 is a top plan view of the confection embodying my design. Fig. 2 is side elevation of the same.

The design consists in a confection, as

shown in the drawings, which comprises a 20 flower-shaped figure, which flower-like figure shows a plurality of petals 1, overlapping each other, the upper edges of such petals terminating in upwardly-extending points 2. The pistil 3 of the flower consists of a bead 25 placed in a central depression in same, and from this the visible edges of the petals radiate. The petals and pistil are of different colors, so as to form a contrast.

I claim as my invention—

The design for a confection, substantially as herein shown and described.

In testimony whereof I affix my signature in presence of two witnesses.

JOSEPH SIMON.
